LOCK FOR AIRPLANE DOORS OR THE LIKE

Samuel Oxhandler, Flushing, N. Y., assignor to
Sargent & Company, New Haven, Conn., a corporation of Connecticut

Application May 24, 1943, Serial No. 488,110

5 Claims. (Cl. 292—39)

This invention relates to locks for closure members such as hatch doors, for example, and is particularly adapted for use with closure members of this character employed upon airplanes. However, while the invention is illustrated and described as particularly related to hatch doors, it will be understood that the structure described and claimed is capable of broad use, and the appended claims are intended to cover the structure described independently of the particular environment in which it may be employed.

The invention is illustrated as applied to doors which are hinged at one side and which are provided with a plurality of bolts extending from the door into the door jamb to hold the former in securely closed position. These bolts are in spaced relation about the edges of the door and, as shown, extend from all of the edges of the door except the hinge edge. This arrangement is particularly suitable for such closure members as hatch doors, for example.

When such doors are used upon airplanes it is desirable that there be no operating members or other elements projecting from the outer surface of the door and, while it is necessary to have some means at the outside of the door for opening the latter, such means should be arranged so that it is flush or substantially flush with the surface of the door to avoid any projecting members.

Also, it is a matter of great convenience if the manually actuating member which serves to withdraw the bolts from locked position also be employed as the member to draw or raise the door to its open position and thus avoid the use of two separate members for these functions. Moreover, it is additionally desirable that this single actuating element be moved in the same direction to accomplish both functions, so that it may, for example, be given an initial movement to withdraw the bolts and an additional or further movement in the same direction to draw or pull the door to open position. Thus anyone desiring to open the door may simply grasp this operating element and, by continued movement of the element in one direction, may first withdraw the bolts to unlock the door and thereafter pull the door to open position.

One object of the present invention is to provide a new and improved lock mechanism for closure members which will be simple in construction and which may be conveniently operated to unlock and open the door.

A still further object of the invention is the provision of a lock mechanism for closure members such as hatch doors for example, the lock-

ing mechanism being provided with a plurality of bolts extending from the edge of the door to hold it in closed position and being provided with a bolt operating or actuating element which serves the double function of withdrawing the bolts and moving the door to open position upon continued movement in the same direction.

A still further object of the invention is the provision of a lock mechanism of the character described, in which the bolt operating member may be retained, when not in use, in a position substantially flush with the outside of the door so that projecting parts or elements are avoided.

A still further object of the invention is the provision of a lock mechanism of the character described in which the manually actuated bolt-operating member is pivoted to the door to swing outwardly about its pivot and in which this member normally is retained in a position substantially flush with the door, the parts being so arranged that this member may first swing outwardly to a position in which it may be grasped by the hand, without affecting the position of the bolts, then be given a further movement in the same direction to withdraw the bolts from their keepers and thereafter be given a further movement in the same direction which serves to pull or draw the door to open position.

To these and other ends, the invention consists in the novel features and combination of parts to be hereinafter described and claimed.

In the accompanying drawings:

Fig. 1 is an outside plan view of a door such as a hatch door, for example, embodying my invention;

Fig. 2 is an elevational view of a like structure upon the inside of the door, i. e., the side opposite that shown in Fig. 1;

Fig. 3 is a sectional view on line 3—3 of Fig. 2;

Fig. 4 is a sectional view on line 4—4 of Fig. 2;

Fig. 5 is a sectional view on line 5—5 of Fig. 2;

Fig. 6 is a view of the bolt-operating member in position corresponding to the dotted line position of the parts shown in Fig. 3;

Fig. 7 is a view similar to Fig. 6 but showing the position of the bolt-operating member when the bolts are fully withdrawn;

Fig. 8 is a view similar to Fig. 3 but showing the parts in the position occupied when the bolts are fully withdrawn, i. e., corresponding to the position of the bolt-operating member shown in Fig. 7;

Fig. 9 is an elevational view of the bolt-operating member, alone; and

Fig. 10 is a similar view of the intermediate

or connecting disk serving to connect the manually operated handle at the outside of the door with the bolt-operating member shown in Fig. 9.

To illustrate the preferred embodiment of my invention I have shown in the drawings a door 10 such as a hatch door for example, hinged at 11 to a body or frame 12, this frame being provided with openings or keepers 13 to receive bolts 14 mounted upon the ends of rods 15 disposed at the inside of the door and pivoted at their inner ends by means of pins 15^a to a bolt-operating or actuating member 16 of disk-like form as shown, for example, in Fig. 9.

While six bolts 14 are shown in Fig. 1 extending to three edges of the door 10, that is to all edges except the hinged edge, the number of bolts employed may, of course, be varied as desired without departing from the scope of the invention. It will also be understood that the device is not limited to hatch doors but may be used upon any closure members to which it may be applicable.

In order that the outside manually operated member for actuating disk 16 may be retained in a position substantially flush with the outer surface of the door 10, the latter is provided with a substantially T-shape opening 17 and upon the inside of the door is secured a housing 18 of similar shape which covers this opening. The housing 18 may be secured upon the door by means of projecting ears 19 and bolts 20 shown more especially in Fig. 2. This housing thus provides a recess or counter-sink within which may lie the operating handle 21 in a position as shown in Fig. 3, in which its outer surface is substantially flush with the outer surface of the door. The housing 18, as stated, is substantially T-shape in form and comprises a longitudinal portion 22 and a horizontal portion 23. At its upper end the longitudinal portion 22 of the housing is offset inwardly as shown at 24 for a purpose to be hereinafter set forth and in this portion of the housing is secured, by rivets 25, a leaf spring 26.

The operating handle 21 is also of T-shape form as shown in Fig. 1 and fits snugly within the opening 17 and housing 18. This member is pivoted at 27 to the lower end of the longitudinal portion of the housing 18 so that it may swing outwardly from its flush position shown in Fig. 3 to the dotted line position shown in that figure and also to the full line position shown in Fig. 8. In order that it may be retained in its flush position, a bolt or catch member 28 is slidably mounted in the upper end of the handle and is urged outwardly by a spring 29 so that the projecting end of this member may enter an opening 31 in the housing 18, the member 28 serving as a latch or bolt to retain the handle in its depressed position within the housing. The end portion 30 of the bolt member 28 may be beveled as is usual with latch bolts for example, so that, when the handle is moved to depressed position, the bolt 28 may be cammed inwardly against the spring 29. In order to release the bolt 28 from its keeper opening 31, a finger piece 32 is secured to the bolt and extends outwardly through a slot 33 in the handle so that it may be conveniently grasped by the fingers of the operator and moved downwardly as shown in Fig. 3. The enlarged portion 24 of the housing 18 permits the upper end of the handle 21 to be enlarged or thickened slightly in order to properly accommodate the bolt 28 and also provides room for the leaf spring

26 which serves to move the handle from its full line to its dotted line position shown in Fig. 3 when the bolt 28 is retracted by the finger piece 32.

5 The housing 18 is provided with a laterally extending supporting member 35, upon which the bolt-operating disk 16 is rotatably mounted by means of the pin 36 and at the end of this member, as shown in Fig. 4, is a pin 37 extending 10 through an arcuate slot 38 in disk 16 which serves to limit the rotation of the disk. The disk 16 is also provided with a second arcuate slot 39 and a short slot 40, the purpose of which will be 15 described hereinafter, it being understood that the pin 36 extends through the central opening 41 in this disk.

20 The means by which the operating handle 21 is connected to the bolt-operating member 16 will now be described. It has already been 25 noted that this operating handle when the finger piece 32 is depressed as shown in Fig. 3 is given an initial movement about its pivot 27 by the spring 26. In order that this initial movement may take place without moving the bolts 14, it is necessary to provide a lost-motion connection between the handle and the bolt-operating member 16 for it would, of course, be disadvantageous to have the bolts moved at this time, as this would require a spring 26 of sufficient strength to effect 30 movements of the bolts.

To this end, I have provided a connecting disk shown at 43 in Fig. 10 which serves as an intermediate motion transmitting member between the handle 21 and operating disk 16. This connecting disk 43 is provided with a central opening 44 by means of which it is pivoted upon the pin 36 which also carries the operating member 16. The disk 43 is also provided with a pin 45 which projects into the slot 40 of the member 16, the slot being longer than the diameter of the pin. This pin-and-slot connection between the two disks serves to connect the two for rotation together but also gives the disk 43 a slight movement independently of the operating member 16 and thus provides sufficient lost motion to enable the spring 26 to move the handle 21 from the full line to the dotted line position shown in Fig. 3 before the pin 45 moves from the lower end of the slot 40 as shown in Fig. 2 to the upper end of this slot as shown in Fig. 6 where it picks up and initiates movement of the member 16.

Upon the lower end of the handle 21, as shown 55 more especially in Figs. 3 and 8, is a gear segment 48 having a plurality of teeth 49 designed to engage within a plurality of openings 50 in the disk 43, so that when the handle is swung about its pivot the teeth 49 will engage progressively in the openings 50 and rotate the disk 43 upon the pin 36. It will be understood that, as shown in Fig. 4 for example, the disk 43 lies immediately behind and abuts the disk 16 and the slot 39 in the latter disk is a clearance slot to permit the projection through this disk of the teeth 49 when the handle 21 is operated.

From the above description it will be seen that the teeth 49 serve to actuate the disk 43 which, in turn, through the pin and slot connection 60 40-45, picks up and rotates the member 16 which serves to withdraw the bolts.

The operation of my device may now be briefly described.

When the door 10 is closed, the parts are in 70 the position shown in the Figures 1 to 4 of the

drawings. The bolts 14 are projected into their keepers and the handle 21 occupies the full-line position shown in Fig. 3 in which it is depressed into the housing 18 in a position flush with the outer surface of the door and is latched in this position by means of the bolt 28. If it is desired to open the door, the finger piece 32 is moved downwardly as shown in Fig. 3 and the end 30 of the bolt 28 withdrawn from its keeper opening. The spring 26 then moves the handle outwardly to the dotted line position shown in Fig. 3. The upper horizontal portion of the handle may now be grasped by the fingers as there is sufficient room to insert the fingers between this portion of the handle and the surface of the door 10.

During this movement of the handle 21, the pin 45 moves from the lower end of the slot 40 as shown in Fig. 2 to the upper end of this slot as shown in Fig. 6 but effects no movement of the disk 16. It is, however, now in position to pick up the disk 16 and a continued movement of the handle will cause movement of this disk, it being understood that during the initial movement of the handle heretofore described the disk 43 has been moved slightly by the engagement of the gear teeth 49 in the openings 50 of the disk 43.

The handle is now pulled toward the observer as shown in Fig. 1, or toward the right as shown in Fig. 3, so as to be given a further movement in the same direction about its pivot 27. This continued movement, as will be clear, serves to move the bolt-operating disk 16 from the position shown in Figs. 2 and 6, to the position shown in Fig. 7, which latter position corresponds to that of the handle shown in Fig. 8. This movement of the disk serves to withdraw the bolts 14 from their keepers and releases the door, and further movement of the member 16 is prevented by means of the engagement of the pin 37 in the slot 38.

A further pull upon the handle 21 in the same direction will now serve to open the door about its hinges 11.

In order to close the door, the reverse of the operations above described is effected. The door is first moved to closed position and the operating handle then moved from the position shown in Fig. 8 to that shown in Fig. 3. This serves to again project the bolts 14 and the handle may be pressed inwardly against the tension of the spring 26 to its depressed position in the housing 18, the beveled end 30 of the bolt 28 permitting this movement and then springing outwardly to latch the handle in this position. It will be obvious that I have provided a bolt-operating mechanism having a handle pivoted on the door in such a relation that the handle is first moved by a spring action from a depressed position to an exposed position in which it may be grasped without effecting any withdrawal of the bolts. A further movement of the handle in the same direction serves to withdraw the bolts while a continued pull upon the handle in the same direction after the bolts are withdrawn serves to draw the door to open position. It will be noted that the handle is pivoted at its end nearest the hinged edge of the door and swings toward this edge of the door so that the movement of the handle is in the same direction as that of the door about its hinges. Also, it may be noted that the initial movement of the handle, that is, the movement to its exposed position, takes place without affecting the position of the bolts. This second movement of the handle serves to move the bolts but does not serve to move the door to

open position; while at the end of this movement the handle is prevented a further movement relatively to the door but its further movement takes place with the door and draws the door to open position.

While I have shown and described a preferred embodiment of my invention, it will be understood that it is not to be limited to all of the details shown but is capable of modification and variation within the spirit of the invention and within the scope of the appended claims.

What I claim is:

1. Door-latching mechanism comprising bolt means, a bolt actuator mounted on the door and connected to said bolt means to actuate the latter, a handle movably mounted on the door and operatively connected to said actuator, said door being provided with a recess in its outer face in which said handle may be depressed to lie substantially flush with the face of the door, said handle being pivotally mounted on the door, means for latching said handle in depressed position, and spring means for moving said handle from such position upon release of said latching means, said actuator comprising a member rotatably mounted on the door, said handle connection thereto comprising a rotatable plate member abutting the actuator and having a pin-and-slot connection therewith, and a toothed element carried by said handle and engaged with said plate member.

2. Door-latching mechanism for a door having an opening through its inner face, a housing designed to be secured to the door opposite said opening, bolt means, a bolt actuator connected to said bolt means to actuate the latter, a supporting member carried by said housing to which said actuator is rotatively secured, a handle pivoted to the housing to lie in a depressed position therein and adapted to swing outwardly through said opening about an axis transverse to the axis of the actuator, said handle being operatively connected to said actuator to rotate the latter by the outward pivotal movement of the handle, and means for latching said handle in depressed position.

3. Door-latching mechanism for a door having an opening through its inner face, a housing designed to be secured to the door opposite said opening, bolt means, a bolt actuator connected to said bolt means to actuate the latter, a supporting member carried by said housing to which said actuator is rotatively secured, a handle pivoted to the housing to lie in a depressed position therein and adapted to swing outwardly through said opening about an axis transverse to the axis of the actuator, said handle being operatively connected to said actuator to rotate the latter by the outward pivotal movement of the handle, and said handle having a lost-motion connection with said actuator.

4. Door-latching mechanism for a door having an opening through its inner face, a housing designed to be secured to the door opposite said opening, bolt means, a bolt actuator connected to said bolt means to actuate the latter, a supporting member carried by said housing to which said actuator is rotatively secured, a handle pivoted to the housing to lie in a depressed position therein and adapted to swing outwardly through said opening about an axis transverse to the axis of the actuator, said handle being operatively connected to said actuator to rotate the latter by the outward pivotal movement of the handle, means for latching said handle in depressed posi-

tion; and spring means for moving said handle outwardly upon release of said latching means.

5. Door-latching mechanism for a door having an opening through its inner face, a housing designed to be secured to the door opposite said opening, a bolt means, a bolt actuator connected to said bolt means to actuate the latter, a supporting member carried by said housing to which said actuator is rotatively secured; and a handle pivoted to the housing to lie in a depressed position therein and adapted to swing outwardly

10

through said opening, said handle being operatively connected to said actuator to rotate the latter upon pivotal movement of the handle; said connections between said handle and said actuator comprising a disk rotatively mounted on said supporting member and having a lost motion connection with said actuator, and said handle having a projection thereon to engage said disk to rotate the latter.

SAMUEL OXHANDLER.
